Primary Examiner — Jennifer Rivard*Assistant Examiner* — April Rivas(74) *Attorney, Agent, or Firm* — Entralta P.C.; Justin G. Sanders; Peter D. Weinstein(57) **CLAIM**

The ornamental design for a segmented container, as shown and described.

DESCRIPTION

FIG. 1 is a perspective view of the segmented container; FIG. 2 is a cross-sectional view of the segmented container, taken along line 2-2 in FIG. 7;

FIG. 3 is a front view of the segmented container shown in FIG. 1;

FIG. 4 is a back view of the segmented container shown in FIG. 1;

FIG. 5 is a left view of the segmented container shown in FIG. 1;

FIG. 6 is a right view of the segmented container shown in FIG. 1;

FIG. 7 is a top view of the segmented container shown in FIG. 1; and,

FIG. 8 is a bottom view of the segmented container shown in FIG. 1.

The broken lines shown are included only for the purpose of illustrating unclaimed portions of the segmented container and form no part of the claimed design.

1 Claim, 6 Drawing Sheets(56)
